UNITED STATES PATENT OFFICE

108,850

DESIGN FOR A TEXTILE FABRIC

Mac Etlinger, New York, N. Y.

Application February 1, 1938, Serial No. 74,787

Term of patent 3½ years

To all whom it may concern:

Be it known that I, Mac Etlinger, a citizen of the United States of America, residing in city of New York, county of New York, and State of New York, have invented a new, original, and ornamental Design for a Textile Fabric, of which the following is a specification, reference being had to the accompanying drawing, forming part thereof.

The figure on the drawing is a plan view of a textile fabric showing my new design.

The dot and dash lines on the drawing show the design unit, which unit is repeated in staggered relation as indicated by the angles A and A'.

I claim:

The ornamental design for a textile fabric, substantially as shown and described.

MAC ETLINGER.
